(**) Term: **14 Years**

(57) **CLAIM**

(21) Appl. No.: **29/327,197**

The ornamental design for universal current leakage testing adapter, as shown and described.

(22) Filed: **Oct. 31, 2008**

DESCRIPTION

(51) **LOC (9) Cl.** **10-04**

FIG. 1 is a top view thereof;

(52) **U.S. Cl.** **D10/78**

FIG. 2 is a side view thereof;

(58) **Field of Classification Search** D10/75,

FIG. 3 is an end view thereof; and,

D10/78, 103; 324/127, 133; 361/45, 98

FIG. 4 is a perspective view thereof.

See application file for complete search history.

The portions shown in shadow line are for illustrative purposes only and form no part of the claimed design.
